UNITED STATES PATENT OFFICE.

DOROTHY SOLOMON, OF NEW YORK, N. Y.

CURTAIN STRETCHER.

Application filed September 6, 1922. Serial No. 586,403.

To all whom it may concern:

Be it known that I, DOROTHY SOLOMON, a citizen of the United States, and a resident of the city, county, and State of New York, have invented certain new and useful Improvements in Curtain Stretchers, of which the following is a specification.

This invention relates to curtain stretchers and has for its primary object to provide a device which may be readily adjusted so that curtains of various sizes can be thereby stretched and held in a taut condition while drying.

It is also one of the important objects of the invention to provide a stretcher frame consisting of a plurality of sections each composed of telescopically engaged parts, one of the parts having a series of spaced fixed pins and the other part a series of similarly spaced adjustable pins which may be disposed in position to receive the curtain in alignment with the fixed pins or moved to an inoperative position so that said pins will not interfere with the telescoping of the frame parts.

It is a further general object of my invention to provide a curtain stretcher as above characterized which is simple and inexpensive in its construction, as well as exceedingly strong and durable, and the several elements of which may be very compactly arranged when the device is not in use and stored in a relatively small space.

With the above and other objects in view the invention consists in the improved curtain stretcher and in the form, construction and relative arrangement of its several parts as will be hereinafter more fully described, illustrated in the accompanying drawing and subsequently incorporated in the subjoined claims.

In the drawing wherein I have disclosed several simple and practical embodiments of the invention and in which similar reference characters designate corresponding parts throughout the several views,

Figure 1 is a perspective view of my improved curtain stretcher illustrating one means for mounting or supporting the same to sustain the curtain in an elevated position;

Figure 2 is an enlarged fragmentary plan view;

Figure 3 is a detail vertical section taken on the line 3-3 of Figure 2;

Figure 4 is a transverse section taken on the line 4-4 of Figure 2;

Figure 5 is a similar section on an enlarged scale taken on the line 5-5 of Figure 2;

Figure 6 is a detail horizontal section taken on the line 6-6 of Figure 5; and

Figure 7 is a fragmentary perspective view illustrating an alternative form of the invention.

In the drawing I have illustrated my improved curtain stretcher as consisting of a plurality of similar parts which are adapted to be secured in assembled relation to form a rectangular frame. Each of the frame parts consists of telescopically engaged sections 5 and 6, respectively. Each of these sections may be conveniently formed with a flat bottom from sheet metal stock. The section 5 is provided along its opposite longitudinal edges with the inwardly turned flanges 7, said flanges at one of their ends terminating in spaced relation to the end of the frame section, such projecting end portion 8 of the frame section having an opening therein to receive a threaded stud or bolt as will be later described.

The flange 7 of the frame section 5 extending along the inner side thereof when the parts of the frame are assembled, is provided with a plurality of equidistantly spaced fixed upstanding pins or studs 9 with which the edge of the curtain is adapted to be engaged. The other flange 7 is provided with suitable graduations indicated at 10, and opposite each of the graduation marks an opening 11 is formed through the body of the sheet metal plate.

The other frame section 6 is likewise provided at its opposite longitudinal edges with the inturned flanges 12 which are adapted to be slidingly engaged in the grooves of the section 5 formed by the flanges 7 thereon. The inner flange 12 of the frame section 6 is provided in its inwardly projecting portion 13 with the spaced notches or recesses 13 to accommodate the pins or studs 14, said pins being hingedly mounted as at 15 upon the underside of the flange. As seen in Figure 5 of the drawings, these hinged pins or studs 14 may be moved to a vertical position so that they project above the flange 12. When so arranged said pins are in substantial alignment with the fixed pins 9 of the frame section 5. When the frame section 6 is tele-

scoped in the frame section 5, the pins 14 are swung inwardly and downwardly to the position seen in dotted lines in Figure 5 so that they will not interfere with such telescoping movement.

The other or outer flange 12 of the section 6 is likewise graduated as shown at 16 and opposite each graduation mark an opening 17 is formed in the body of the metal plate. It will be understood that the two sections 5 and 6 constitute one side of the stretcher frame and after proper relative adjustment in accordance with the desired length or width of the frame, a bolt 18 is inserted through coinciding openings 11 and 17 in the frame sections and a wing nut 19 engaged on said bolt and adjusted into tight clamping engagement against the underside of the frame section 5.

After each side member of the frame has been adjusted to the required length as above explained, the end portions 8 are arranged in overlapping relation. When a lawn or grass plot is available upon which the stretcher frame may be placed, the side members of the frame may be readily clamped together by inserting ordinary bolts through the coinciding openings in the end portions 8 of the frame members and adjusting the clamping nuts thereon. When the curtain is to be dried in the house, however, the frame may be conveniently set up in the room by the use of the supporting legs 30, each of said legs having a stud bolt 21 fixed in its upper end adapted to be engaged through the openings of the end portions 8 of the frame members. Suitable clamping nuts 22 are then adjusted upon the threaded ends of said bolts to rigidly secure the several parts of the frame in assembled relation. It will of course also be understood that in lieu of the supporting legs a suitable easel of any desired construction may be employed.

In Figure 7 of the drawing I have illustrated a slightly modified form of the device wherein the inwardly projecting portion of the inner flange 12 of the frame section 6 may be omitted. A rod 23 is mounted in suitable bearings 24 along the inner side of the vertical flange 12' at its juncture with the body of the sheet metal plate and upon this rod the spaced wire pins 25 are hingedly engaged at one of their ends. When said pins are disposed in the position seen in full lines in Figure 7, they are below the upper edge of the flange 12' so that the frame section 6 can be readily moved into or out of the frame section 5. After adjustment these pins 25 may be raised to a vertical position and the curtain engaged thereon. The pull of the curtain holds said pins closely against the inner side of the flange 12' which limits their swinging movement in one direction.

From the foregoing description considered in connection with the accompanying draw-

ings, the construction, manner of use and several advantages of my present invention will be clearly and fully understood. It will be seen that the improved curtain stretcher is quite simple in its construction, as well as strong and durable. The several frame members can be very easily and quickly adjusted so that curtains of various sizes can be properly stretched upon the frame. I have indicated in the drawing that each of the frame members may be adjusted to a minimum length of two foot up to a maximum length of four feet. However, it will of course be apparent that if desired, each of the telescoping frame sections can be made of greater length so as to obtain a greater range of adjustment. When the stretcher is not in use, the several frame sections may be disconnected and arranged in very compact relation so that the device can be stored away in a relatively small space.

In Figure 5 is shown one embodiment on an enlarged scale. In practice it is made much smaller; about the size of an ordinary pin-head.

It is clear that the embodiment shown in Figure 5, on a smaller scale, may be used in place of the pins shown in the embodiment of Figure 7. So, for instance, the frame shown in Figure 1, which shows the stud embodiment, may be made up in the form of pins, like the embodiment shown in Figure 7.

I have shown and described several practical and satisfactory embodiments of the device, but it will nevertheless be understood that the stretcher might be produced in various other alternative constructions. Accordingly, I reserve the privilege of resorting to all such legitimate changes in the form, proportion and relative arrangement as may be fairly embodied within the spirit and scope of the invention as claimed.

I claim:

1. A curtain stretcher comprising frame members each consisting of two flat telescoping sections of unequal width, each section being provided with longitudinally extending lateral flanges having their ends spaced from the ends of said sections, the outer section being provided with a plurality of fixed curtain attaching pins, the inner section having a plurality of recesses formed in one of its flanges and a plurality of curtain attaching pins hingedly connected to the flange of said section and adapted to be moved within the recesses of said flange into alignment with the fixed pins of the outer section when in use, or to be pressed inward to permit the sections to be telescoped together.

2. A curtain stretcher comprising frame members each consisting of two flat telescoping sections of unequal width, each section

being provided with longitudinally extending lateral flanges having their ends spaced from the ends of said sections, the outer section being provided with a plurality of fixed curtain pins, the inner section having a plurality of hinged attaching pins movable into a vertical position in line with the fixed

pins of the outer section and adapted to be pressed inward to permit the sections to be telescoped together.

10

In testimony that I claim the foregoing as my invention, I have signed my name hereunder.

DOROTHY SOLOMON.
